UNITED STATES PATENT OFFICE.

JULIUS PERSANOWSKY, OF BROOKLYN, NEW YORK.

WASHING-MACHINE.

SPECIFICATION forming part of Letters Patent No. 431,821, dated July 8, 1890.

Application filed April 4, 1889. Serial No. 306,034. (No model.)

To all whom it may concern:

Be it known that I, JULIUS PERSANOWSKY, a citizen of the United States, residing at Brooklyn, in the county of Kings and State of New York, have invented certain new and useful Improvements in Washing-Machines, of which the following is a specification.

The object of my invention is to provide a new and improved washing-machine which is simple in construction and effective in use.

The invention consists in the construction and combination of parts and details, as will be fully described hereinafter, and finally be pointed out in the claim.

15 In the accompanying drawings, Figure 1 is a vertical longitudinal sectional view of my improved washing-machine, parts being broken out. Fig. 2 is a horizontal sectional view on the line $\alpha\alpha$, Fig. 1. Fig. 3 is a horizontal sectional view on the line $\gamma\gamma$, Fig. 1; and Fig. 4 is a plan view of the machine, parts being broken out.

Similar letters of reference indicate corresponding parts.

25 The tub A has a series of parallel ribs B on the upper surface of its bottom and a series of upwardly-projecting ribs C on the inner surface of its side walls. The cover D is provided with a hinged part E, and in the same 30 a shaft F is mounted to rotate and projects from the upper and lower surfaces of the hinged section, said shaft F being on the central line of the tub. On that end of the shaft projecting from the top of the cover a cog-wheel G is rigidly mounted, which engages a larger cog-wheel H, mounted on a pin H' on a plate J on the upper surface of the hinged section, through an aperture in which plate 35 J the shaft F passes. The cog-wheel H engages the cogged segment or semicircle K, mounted to rock on a pivot K' of the plate J, a handle or hand-rest L being formed on the upper end of said pivot K'. The cogged segment or semicircle J is provided with a 40 socket M for receiving one end of the handle-bar N. A cog-wheel O is fixed on the under side of the hinged part E of the cover, and through the center of said cog-wheel the shaft F passes loosely. On that end of the shaft 45 F below the hinged section of the cover a horizontal frame or plate P is secured, in each end of which a fluted rubbing-roller Q is

mounted to rotate, said rollers Q projecting downward from the under side of the frame P, their lower ends being a short distance 55 from the bottom of the tub. The pivots of the rollers Q project above the frame P, and their upper ends carry pinions R, engaged at diametrical opposite points with the fixed cog-wheel O. When the hinged part of the cover 60 is swung up, the fluted rollers Q are removed with the same from the tub. As the cog-wheels on the upper surface of the hinged cover-section are supported by the plate J and as the fluted rollers are supported by the 65 frame P, the entire device can readily be applied to or detached from the tub.

The clothes are placed into the tub with the necessary quantity of soap and water, the cover is swung down and fastened, the 70 left hand of the operator is placed on the handle-bar L, the end of the handle-lever N is placed in the socket M, and said handle-lever rocked to and fro, whereby the shaft F is rotated alternately in opposite directions at great speed, and the frame P, which is connected with the shaft F, is likewise rotated in opposite direction alternately. The rollers Q are rotated alternately in opposite directions around the vertical central 75 line of the tub, and at the same time are rotated also in opposite directions on their own axes. They agitate the water very thoroughly, causing the same to carry the clothes around alternately in opposite directions, the clothes 80 being thoroughly rubbed by the fluted rollers and the ribs on the inner surface of the tub.

Having thus described my invention, I claim as new and desire to secure by Letters Patent—

90

In a washing-machine, the combination, with a tub having ribs on its sides and bottom, of a cover, a cog-wheel secured on the under side of said cover, a shaft mounted to rotate in said cover and passed loosely through 95 said cog-wheel on the under side of the cover, a cross-piece secured on the lower end of said shaft, downwardly-projecting fluted rollers mounted at their upper ends only to turn in said cross-piece and having the lower ends 100 free, cog-wheels on the upper ends of the shaft of said rollers and engaging the fixed cog-wheel on the under side of the cover, a cog-wheel on the upper end of the shaft in said

cover, a rocking handle-lever on the cover, gearing for transmitting motion from said rocking handle-lever to the cog-wheel on the upper end of the shaft in the cover, and a 5 fixed handle projecting upward from the pivot of the rocking handle, substantially as set forth.

In testimony that I claim the foregoing as my invention I have signed my name in presence of two subscribing witnesses.

JULIUS PERSANOWSKY.
